UNITED STATES PATENT OFFICE.

ROBERT R. ROBERTSON, OF LA GRANGE, ILLINOIS.

AQUEDUCT.

1,187,930.

Specification of Letters Patent. Patented June 20, 1916.

Application filed May 8, 1915. Serial No. 26,787.

To all whom it may concern:

Be it known that I, ROBERT R. ROBERTSON, a citizen of the United States, residing at La Grange, in the county of Cook and State 5 of Illinois, have invented new and useful Improvements in Aqueducts, of which the following is a full, clear, concise, and exact description, reference being had to the accompanying drawing, forming a part of this 10 specification.

My invention relates to aqueducts, and more specifically to means for providing a water tight joint between adjacent sections of sheet material which are connected together to form the aqueduct.

Among the objects of my invention is to provide a device of this character which will be simple in construction and efficient in use.

Further objects will appear from the detailed description to follow and from the appended claims.

In the drawings in which I have shown various modifications of my invention—Figure 1 is a perspective view showing a 25 form of connecting device which is formed from a single strip of sheet material; Fig. 2 is a side elevation of two sections of the aqueduct showing the corners of the sections bent over to provide means for engaging the 30 connecting strip to properly position the parts; Fig. 3 is a side elevation showing the sections and clamping band in position; Fig. 4 is a transverse section showing the clamping band before the ends are rolled together 35 to form the joint between the sections; Fig. 5 is a transverse section showing the ends of the clamping band rolled together to force the aqueduct sections into water tight engagement with each other; Fig. 6 is a plan view showing the two sections and clamping band in position and the ends of the clamping band rolled together, and showing also the key or tool for engaging the ends of the clamping band; Fig. 7 is a perspective view 40 of the key or tool for rolling the ends of the clamping band together; Fig. 8 is a transverse section of a modification in which the device for making a water tight connection comprises two strips, each having one of its 45 ends firmly secured to an end of the other strip, the opposite ends of the strips being 50 rolled together to force the aqueduct sec-

tions together; and Fig. 9 is a transverse section of a still further modification in which the clamping device is formed of a 55 single integral strip of sheet material bent upon itself and having one end bent over the other to prevent slippage.

Referring now to the drawings in detail, and first to Figs. 1 to 6, I have shown my 60 device in connection with an aqueduct comprising sections 10 which may be of sheet metal and which have their corners bent over, as shown at 11, forming projections for engagement with the connecting and clamping device 12, to properly position the sections with respect thereto, and to hold the connecting device in place. The connecting device 12 comprises an integral strip of suitable material, such as sheet metal, bent back 70 upon itself, as shown at 13, to form an outer curved portion 14 for engagement with the outer section 10, and an inner curved portion 15 for engagement with the inner section 10. The ends of the portions 14 and 75 15 extend upwardly beyond the sections 10, as shown at 16, in position to engage the slot 17 of a tubular key or tool 18 a portion of which is flattened, as shown at 19, for engagement with a wrench or other suitable 80 tool, whereby the projecting ends 16 may be rolled together, as shown at 20, Fig. 5.

In this device there are two ways in which the aqueduct sections and clamping band may be assembled; the sections 10 may be 85 placed with their ends overlapping and one within the other and the ends 16 of the clamping device separated slightly to permit the device to be slipped in place by straddling both sections until the parts are 90 in the position shown in Fig. 4, after which the ends 16 may be rolled together until they are in the position shown at 20 in Fig. 5, or the clamping device 12 may be slipped in place over the end of one of the sections 10 95 and slipped along the section far enough to allow the end of another section 10 to be overlapped on the first section, after which the clamping device 12 may be slipped back until the portions 14 and 15 lie between the 100 projections 11 on the overlapping sections 10, after which the ends 16 of the clamping device are rolled together.

In rolling the ends 16 together the first

effect of turning the key or tool 18 is to make a sharp bend in the ends 16 to prevent relative slippage therebetween. Further turning of the key 18 will result in winding 5 the outer portion 14 around the inner portion 15.

As the portion 14 is wound on the outside a greater length of the outside portion will be wound up on the roll which will result 10 in drawing the portions 14 and 15 closer together and clamping the sections 10 between them to form a water tight joint.

In the modification of Fig. 8 the clamping device 21 comprises an outer strip 22 and an 15 inner strip 23, which may be of sheet metal, one end of each of which are clamped together, as shown at 24, and the other ends of which may be rolled together by means of the tool 18, as shown at 25, to clamp the sections 20 10 together in a manner similar to that described in connection with Figs. 1 to 6.

In the modification of Fig. 9, the clamping device is formed of a single strip which may 25 be of sheet metal, which is bent upon itself to form outer and inner sections 26 and 27, the end of the outer section being bent over the end of the inner section, as shown at 28, to prevent relative slippage between the sections. In this modification the projecting 30 ends 29 may be rolled together by means of pliers or other suitable instruments without the aid of a special tool.

While in the various modifications I have 35 shown the clamping device as holding the aqueduct sections together in overlapping position so that the water tight joint is formed between the aqueduct sections themselves, it is obvious that the aqueduct sections may 40 be placed together to form a butt joint and the clamping device placed in position to engage an end of each section and the ends of the clamping device rolled together, in which case the water tight joint 45 will be formed between the inner strip of the clamping device and the inner surface of the aqueduct sections.

Having thus described my invention what I claim as new and desire to secure by Letters Patent is:

1. The combination with two overlapping trough-like sections of an aqueduct, of means 50 for forcing said sections into water tight engagement with each other comprising a compression member engaging the inner section, a tension member engaging the outer section, and means for exerting compression on said compression member and tension on said tension member, said last means comprising means for rolling said tension member about said compression member.

2. A device for forcing two overlapping curved sections of an aqueduct into water tight engagement comprising a curved com-

pression member for engagement with the 65 inner section, and a curved tension member for engagement with the outer section, both said members having flexible inter-engaging portions for extending beyond the edge of the aqueduct, said interengaging portions 70 being of sufficient flexibility to permit one of said portions to be rolled about the other and means for rolling one of said members about the other.

3. A device for forcing two overlapping 75 curved sections of an aqueduct into water tight engagement comprising a curved compression member for engagement with the inner section, and a curved tension member for engagement with the outer section, each 80 of said members comprising a single integral piece of sheet material, one end of the tension member being rolled about the adjacent end of the compression member.

4. A device for forcing two overlapping 85 curved sections of an aqueduct into water tight engagement comprising a curved compression member for engagement with the inner section, and a curved tension member for engagement with the outer section, both 90 said members having flexible inter-engaging portions for extending beyond the edge of the aqueduct whereby a portion of said tension member may be bent around a portion of the compression member, and means for 95 bending said portions comprising a tube having a slot in its side to receive the ends of said inter-engaging portions.

5. The combination with two trough like 100 sections of an aqueduct, of means for effecting a water tight joint therebetween comprising two members of sheet material of sufficient flexibility and so constructed and located relative to each other that one may be readily rolled about the other.

6. The combination with two trough-like 105 sections of an aqueduct, of means for connecting said sections to form a water tight joint comprising a compression member engaging the inner surface of one of said sections, a tension member engaging the outer surface of one of said sections, and means for exerting compression on said compression member and tension on said tension member, said last means comprising means 110 for rolling said tension member about said compression member.

7. The combination with two trough-like 115 sections of an aqueduct, of means for effecting a water tight joint therebetween comprising two members of sheet material of sufficient flexibility and so constructed and located relative to each other that one may be rolled about the other and means for rolling one of said members about the other.

8. A device for effecting a water tight connection comprising inner and outer curved members of sheet material, means for prevent-

ing relative movement between one end of the inner member and one end of the outer member, and means for causing relative movement between the other ends to draw the 5 members toward each other, said last means comprising two members of sheet material of sufficient flexibility and so constructed

and located relative to each other that one may be rolled about the other and means for rolling one of said members about the other. 10

In witness whereof, I have hereunto subscribed my name in the presence of two witnesses.

ROBERT R. ROBERTSON.
